UNITED STATES PATENT OFFICE.

RUFUS Y. KIRKLAND, OF WOODHAVEN, AND JOHN REED, OF NEW YORK,
N. Y.

SINK-CLEANER.

SPECIFICATION forming part of Letters Patent No. 388,880, dated September 4, 1888.

Application filed February 15, 1888. Serial No. 264,152. (No model.)

To all whom it may concern:

Be it known that we, RUFUS Y. KIRKLAND and JOHN REED, citizens of the United States, residing at Woodhaven, in the county of 5 Queens and State of New York, and New York city, in the county and State of New York, respectively, have invented certain new and useful Improvements in Sink-Cleaners; and we do declare the following to be a full, clear, 10 and exact description of the invention, such as will enable others skilled in the art to which it appertains to make and use the same, reference being had to the accompanying drawings, and to the letters and figures of reference 15 marked thereon, which form a part of this specification.

Our invention consists of a combined scraper for collecting the refuse in the sink and a perforated shovel for removing the refuse, and 20 the improved means for securing the scraper to the shovel-handle, hereinafter described and claimed.

In the accompanying drawings, forming part of this specification, Figure 1 is a face 25 view of our complete sink-cleaner. Fig. 2 is a longitudinal section of same. Fig. 3 is an enlarged face view of the blank for the scraper portion as before bending to secure the scraper. Fig. 4 is an end view of the scraper.

30 The complete sink-cleaner consists of scraper part *a*, handle *b*, and perforated shovel *c*, made of a blank stamped in one piece out of sheet metal, and a strip of rubber, *h*, or any suitable material secured in the upper end of 35 the handle and forming scraper part *a*. The metallic blank is first stamped out with its scraper-holding part in the form represented in Fig. 3, with the lateral projections indicated in dotted lines *d*, and with the punched 40 holes *e*, also with the perforations *g* in the shovel *c*. The blank is then folded back and forward on the lines *f*, as indicated in Fig. 2, with the rubber or other equivalent scraper inserted in the last fold, which, being tightly 45 pressed together, secures the rubber in the scraper-shank. The perforations shown in center fold of Fig. 3 are intended for more effectually securing the rubber without any other

fastening for the rubber, as when the metal is folded down upon the rubber it will be compressed around and made to swell into the perforations, and thus be securely fastened without any rivets or pins, and the method of fastening will be entirely hidden in the folding of the metal. To make the ends of the scraper-holding part more secure, we also stamp the blank out with the wings or lateral projections *d*, (shown in Fig. 3,) and fold them to the back of the rubber or scraper, as shown in Fig. 4.

In use the scraper *a* will be used for scraping together the solid refuse which will not pass through the sieve into the waste-pipe of the sink, and the shovel part *c* for removing the said refuse from the sink, the perforations 65 of the shovel allowing the water to drain away from the solid portion of the refuse, which, being thus separated from the water, may be thrown into the fire and burned, or be otherwise more favorably disposed of than without separation.

What we claim, and desire to secure by Letters Patent, is—

1. A sink-cleaner having the scraper-rubber *h* secured by compression in the folds of the 75 scraper-shank, the said folded part of the shank having the perforations *e* to receive the portions of the imperforate rubber forced into them by the compression of the fold of the shank, substantially as described.

2. In a sink-cleaner having the scraper-rubber *h* secured in the folds of the scraper-shank, the combination, with said rubber and the main fold of the shank turned over the edge of the rubber, of the lateral projections *d*, 85 folded around the ends of the rubber and the ends of said main fold, substantially as described.

In testimony whereof we affix our signatures in presence of two witnesses.

RUFUS Y. KIRKLAND.
JOHN REED.
